TSUNEJIRO NOMOTO, OF SEATTLE, WASHINGTON.

COMBINATION SALT-CELLAR AND PEPPER-BOX.

1,164,387.

Specification of Letters Patent. Patented Dec. 14, 1915.

Application filed October 8, 1914. Serial No. 865,735.

To all whom it may concern:

Be it known that I, TSUNEJIRO NOMOTO, a subject of the Emperor of Japan, residing at Seattle, in the county of King and State of Washington, have invented certain new and useful Improvements in Combination Salt-Cellars and Pepper-Boxes; and I do hereby declare the following to be a full, clear, and exact description of the invention, 10 such as will enable others skilled in the art to which it appertains to make and use the same.

This invention relates to receptacles and serving devices for condiments or other powdered material where it is desired to sprinkle a plurality of such materials independently from the same receptacle.

One object of the invention is to provide a container having a partition therein dividing the container into separate chambers for containing the condiments or other materials, such chambers having openings and closures for the openings with means for selectively opening the closures manually to discharge either of the materials from its respective chamber.

A further object of the invention is to provide in a device as above described means whereby the termination of the discharge 30 of one of the materials from the container serves to shift the mechanism automatically so that the next material discharged is the other material.

With these and other objects in view the invention comprises certain novel constructions, combinations and arrangements of parts as will be hereinafter more fully described and claimed.

In the drawings: Figure 1 is a vertical 40 diametrical sectional view through the device. Fig. 2 is a transverse sectional view taken on line 2—2 of Fig. 1. Fig. 3 is a bottom plan view of the device with the sifting cover removed as indicated by line 45 3—3 of Fig. 1.

Like characters of reference designate corresponding parts throughout the several views.

The improved serving device which forms 50 the subject-matter of this application comprises a container 10, of conventional tumbler shape having a screw cap 11 at its upper or larger end and a perforated sifting cap 12 at its lower or smaller end, the latter engaging the flange of a reduced portion or

neck 13, such reduced neck forming a shoulder 14.

Disposed diametrically within the container 10 is a partition 15 properly proportioned to intimately engage the tapered sides 60 of the container 10 and rest upon the shoulder 14 and carrying a bottom in the form of a disk 16 proportioned to fit intimately within the reduced neck 13. The partition 15 as will be apparent from Fig. 2 divides the container into two opposite semi-circular chambers and the bottom 16 is provided with two openings 17 and 18 which form communication between the respective semi-circular chambers and the space between the bottom 70 16 and the sprinkler cap 12. To the bottom are pivoted closures 19 and 20 held yieldingly closed by the springs 21 and 22 to normally cover the openings 17 and 18 and prevent the discharge of any material from 75 the semi-circular chambers to the sifting cap. The bottom 16 is provided with a central stop 23 against which the tails of the closures 19 and 20 engage as indicated at Fig. 3 under the tension of the springs 21 80 and 22.

Upon one side the partition 15 is provided with a housing comprising the flange 24 and cover 25 with a rib 26 disposed intermediate between the substantially parallel 85 sections 24' of the flange. The intervals between the rib 26 and the sections 24' of the flange form guides for plungers 27 and 28 and direct them through slots 29 and 30 in the bottom 16. The plungers have cam extremities 31 and 32 to engage the tails of the closures 19 and 20, one being shown in such position at Fig. 3. The plungers 27 and 28 are held normally and yieldingly upwardly 90 out of engagement with the closures 19 and 95 20 by springs 33 and 34 respectively.

To force the plungers 27 or 28 downwardly to open their respective closures a block 35 is mounted to slide in the housing, and this block is controlled by a stem 36 100 moving in a guide and held normally yieldingly raised by the spring 37. The stem 36 is provided with a button 38, and a disk 39 is carried upon the housing 24 of a diameter similar to that of the button so that the screw cap 11 may be removed without removing the button 38. The block 35 carries a finger 40 pivoted thereto as at 41, and adapted to be swung from side to side to engage either of the plungers 27 or 28 when 110

the button 38 is depressed, such swinging being brought about manually by tilting the receptacle. In the position shown at Fig. 1 it is obvious that when the button 38 is depressed the finger 40 will engage the plunger 27 and forcing that downward serves to open the closure 20. If the device is tilted in the opposite direction the finger 40 will swing to similarly engage the plunger 28.

Within the housing are mounted kicker levers 41 and 42 by pivoting at 43 and 44 respectively, and expansive springs 45 and 46 are provided to throw such levers normally inward toward the finger 40. The levers 41 and 42 are provided with reduced or spring lower ends constituting latches having hooked extremities 47 and 48 which extend through openings between the housing 24 and the abutment 49. The plungers 27 and 28 carry spring pressed detents 50 and 51 having cam faces which permit such detents to ride over the extremities 47 and 48 of the latches while the plungers are being depressed, but to engage such extremities when the plungers are raised. When, therefore, one of the plungers is depressed and permitted to return under the action of its spring 33 the detent 50 lifts the latch 47 out of engagement with the angle in the section 24' and permits the spring 45 to throw the kicker 41 over against the finger 40 and swing such finger to the opposite side.

Assuming therefore that the positions of the parts as shown at Fig. 1 are such that the depressing of the button 38 will release salt from one of the chambers by the depressing of the plunger 27 when such plunger is returned, the kicker 41 will automatically swing the finger 40 to the opposite side so that by again depressing the button 38 such finger engages the plunger 28 and releases pepper. The lower end of the block 35 is wedge-shaped as at 35' and stands between the upper ends of the kickers as shown, and at each descent of the stem and block either kicker which may have been thus released and permitted to act is restored and its hooked extremity relatched. If, therefore, one desires to apply both condiments or materials in succession it is only necessary to depress the button 38 twice and shake the receptacle thereby securing a supply of both of the materials. While the words Salt and Pepper appear in the drawing at Fig. 1 upon the screw cap 11 it is obvious that any other words may be substituted therefor if such condiments are not to be employed in the receptacle. Assuming, however, that salt and pepper are the condiments to be applied the initial operation would be to tilt the container toward the side indicated "Salt", which would swing the finger 40 to the position shown at Fig.

1. The depressing of the button would then cause the release of salt from its chamber and the release of the button would cause the lever 41 to kick the finger 40 to the opposite side so that a second depressing of the button 38 would cause the release of pepper. It is obvious, of course, that the device might be initially tilted toward the word "Pepper", and pepper be the first to be released and it is not necessary then to release the other condiments unless it is desired.

I claim:

1. In a condiment holder, the combination with an upright container internally divided into a pair of chambers and whose bottom has openings respectively communicating with them, and a perforated cap carried by the container below its bottom and spaced therefrom; of closures for said openings, devices for opening said closures, an element for actuating said devices, and means for moving said element manually into selective engagement with either of said devices. 80

2. In a condiment holder, the combination with an upright container internally divided into a pair of chambers and whose bottom has openings respectively communicating with them, and a perforated cap carried by the container below its bottom and spaced therefrom; of closures for said openings, devices for opening said closures, an element for actuating said devices, 85 means for moving said element manually into selective engagement with either of said devices. 90

3. In a condiment holder, the combination with an upright container internally divided into a plurality of chambers and whose bottom has openings respectively communicating with them, and a perforated cap carried by the container below its bottom and spaced therefrom; of closures for said openings, mechanism for selectively opening the closures to throw either chamber into communication with the space, a cap for the upper end of the container, and 100 a shank passing slidably through said cap and connected with said mechanism. 105

4. In a condiment holder, the combination with a container having openings at the bottom, closures normally closing said openings, and an internal partition dividing the container into chambers respectively communicating with the openings; of plungers slidably mounted on said partition and held normally raised, their lower ends being 110 shaped to open said closures when the plungers are depressed, a vertically movable and manually operable element, and a movable support for said element whereby it is 115 adapted to be aligned with either of said 120 125 130

plungers for selectively operating them when it descends.

5. In a condiment holder, the combination with a container having openings at the bottom, closures normally closing said openings, and an internal partition dividing the container into chambers respectively communicating with the openings; of plungers slidably mounted on said partition and held normally raised, their lower ends being shaped to open said closures when the plungers are depressed, a stem moving in a guide on said partition and having a button at its upper end, and a finger pivoted at its upper end to said stem and having its lower end adapted to be swung over said plungers for selectively operating them when it descends.

6. In a condiment holder, the combination with a container having openings at the bottom, closures normally closing said openings, an internal partition dividing the container into chambers respectively communicating with the openings; and plungers slidably mounted on said partition and held normally raised, their lower ends being shaped to open said closures when the plungers are depressed; of a flange on said partition loosely embracing said plungers and formed at its upper end into a guide, a manually operable stem slidably mounted in the guide and having a block at its lower end, a spring normally raising said stem and block, and a finger pivoted at its upper end to the block with said lower end swinging within the flange and adapted to be selectively engaged with the upper ends of the plungers.

7. In a condiment holder, the combination with a container having openings at the bottom, closures for said openings, an internal partition dividing the container into chambers respectively communicating with the openings; and plungers held normally raised, their lower ends being shaped to open said closures when the plungers are depressed; of a housing comprising a flange on one side of said partition having parallel sections at its lower end outside said plungers and a guide at its upper end surrounded by a disk, a rib between said plungers, and a cover plate overlying the sections and rib; a cap for the container having a central hole fitting around said disk, a normally raised stem sliding in said guide and having a button above and no larger than the disk, and a finger pivotally connected with the lower end of the stem and adapted to swing within the housing so that its lower extremity may be selectively engaged with said plungers.

8. In a condiment holder, the combination with a container having openings at the bottom, closures for said openings, an internal partition dividing the container into

chambers respectively communicating with the openings; and plungers held normally raised, their lower ends being shaped to open said closures when the plungers are depressed; of a guide on one side of said partition surmounted by a disk, a cap for the container having a central hole fitting around said disk, a normally raised stem sliding in said guide and having a button above and no larger than the disk, and a finger pivotally connected with the stem and adapted to swing so that it may be selectively engaged with said plungers.

9. In a condiment holder, the combination with a container whose bottom is provided with a pair of openings, closures pivoted to said bottom, and springs for drawing the closures over the openings; of a partition dividing the container into compartments communicating with said openings, plungers guided on the partition and having cam extremities adapted to open the closures when the plungers are depressed, springs normally raising said plungers, a manually operable stem slidably mounted in the upper end of said container, a finger pivoted at its upper end to said stem with its lower end free and adapted to be swung over either plunger by tilting the entire device, and means for kicking the finger into position over the opposite plunger on the rise of that plunger which the finger has depressed.

10. In a condiment holder, the combination with a container having two outlets in its bottom and a partition between them, a pair of normally raised plungers adapted to open the outlets when they are depressed, and manually operable devices including a swinging finger for engaging and selectively depressing said plungers; of a housing on the partition, kickers pivoted in said housing, means for throwing their upper ends normally toward the finger, latches for holding said ends outward, a detent on each plunger for tripping the adjacent latch as the plunger ascends, and means on said devices for spreading said ends.

11. In a condiment holder, the combination with a container having two openings in its bottom, closures normally covering said openings, a partition dividing the container into compartments communicating with the openings, a pair of normally raised plungers whose lower ends are adapted to open the closures when they are depressed, and manually operable devices for selectively depressing said plungers, such devices including a pivoted finger; of a housing on the partition embracing said plungers and devices, kickers pivoted in said housing, springs throwing their upper ends normally toward the finger, latches at their lower ends for holding said upper ends outward, means on each plunger for tripping the ad-

jacent latch as the plunger ascends, and means on said devices for spreading the upper ends of the kickers.

12. In a condiment holder, the combination with a container having two outlets and compartments communicating therewith, closures for said outlets, a pair of normally raised plungers adapted to open the closures when they are depressed, a manually depressible wedge-shaped block, and a swinging finger on the block for selectively depressing said plungers; of a housing in the container, kickers pivoted in said housing, springs throwing their upper ends normally

toward the finger and into the path of said block so that the latter will spread such ends when it descends, hook-shaped spring latches at their lower ends for engaging said housing and holding said upper ends outward, and a spring-projected detent in each plunger for tripping the hook of the adjacent latch as the plunger ascends.

In testimony whereof I affix my signature in presence of two witnesses.

TSUNEJIRO NOMOTO.
